JOHN A. MORRISON, OF SEATTLE, WASHINGTON, ASSIGNOR TO SAFETY SIGNAL COMPANY, A CORPORATION OF WASHINGTON

CROSSING SIGNAL

Original application filed December 4, 1926, Serial No. 152,622. Divided and this application filed December 20, 1927. Serial No. 241,279.

This invention relates to railroad crossing signals, and more particularly to "lightning flash signals". The present application is a division of my co-pending application, Serial 5 No. 152,622, filed December 4th, 1926. In said previously filed application I have disclosed a signalling casing, having a zig zag sight opening in its side, and a plurality of lights arranged to illuminate said casing and 10 to produce an effect in close simulation of a flash of lightning.

The signal of the present invention, like the signal of the parent application referred to, is particularly intended for use at railway 15 crossings. With the rapid increase in automobile traffic, the toll of human life taken at grade crossings has heavily increased in the past few years. I am well aware of the fact that warning signals, both audible and visible, at railroad crossings, are not new. However, there are so many warning lights displayed upon the highways, and so many attention attracting lights displayed for advertising purposes along the highways, such as at 20 inns, refreshment stands, and the like, that the ordinary visual signal has largely lost its value, as far as indicating the existence of a railroad crossing is concerned.

Therefore, one of the principal objects in 30 view, both in my parent application, aforesaid, and in this divisional application, is to provide a railroad crossing signal which will be so distinctive in appearance that there will be no danger of its being confused with any 35 other visual signal. This is accomplished by providing a visual signal which will repeatedly flash in imitation of a streak of lightning. Consequently, it will be seen that not only is the signal one which is not likely to 40 be confused with any other signal, but it simulates something that the human mind has associated with danger, throughout the ages.

In the accompanying drawing, 45 Figure 1 is an elevation of a signal, constructed in accordance with the invention, Figure 2 is a view, partly in side elevation, and partly in vertical section through the signal casing,

50 Figure 3 is a diagrammatic view of one

form of wiring which may be employed, and Figure 4 is a sectional view of the flashing element, hereinafter described.

Like numerals designate corresponding parts throughout the several figures of the 55 drawing.

In the drawing, 5 designates a signal pole, which may have mounted, at its top, an audible signal 6. This signal 6 may be a bell, a whistle, or the siren of my parent application, above referred to. The visual signal comprises a casing 7, having opposite side walls 8 and 9. These walls are opaque, except for sight openings 10. These sight openings are of zig zag formation to simulate the conventional representation of a streak of lightning. Electric lamps, which may be disposed at any desirable point within the casing 7, are indicated at 11, 12, 13 and 14, though the number of these lamps may be 65 varied as conditions require. These lamps are arranged in parallel in an electric circuit 15, and are controlled by a rotative flasher 16, of conventional formation comprising a plurality of arcuate segments 16^a, 16^b, 16^c, 16^d. Segment 16^b is slightly longer than segment 16^a, and 16^c is slightly longer than 16^b, and so on, so that the lamps will be successively energized.

Since these lamps are disposed at spaced positions longitudinally of the casing 7, it follows that the illumination visible through the sight opening will appear to be travelling longitudinally of the casing, and thus will produce an effect similar to that of a flash of lightning. This effect may be accentuated by disposing each lamp in a separate compartment, said compartments being formed by partitions 17. I have indicated the circuit 15 as including a source of E. M. F. 70 18, audible signal 6, and a section of railroad track 19, it being understood that the presence of a train in that particular section of track, which may be insulated at 20 from adjacent sections of track, will result in completing the circuit, sounding the audible 75 signal 6, and flashing the lights 11 to 14, in succession.

The claims in my co-pending application, aforesaid, include the audible signal, and the mechanism thereof, more or less broadly.

The present application is intended to cover the lightning flash signal per se, irrespective of whether it is employed with an audible signal or not, and irrespective of the nature of the audible signal employed therewith.

It is apparent that many ways of arranging the lamps and partitions will readily suggest themselves to persons skilled in the art.

10 While I prefer to energize the lights in the order desired, it is apparent that a more jerky effect can be secured by energizing the lights in the following order, 11, 13, 12 and 14, and it is to be understood that the invention is not limited to the particular order in which the lights are energized.

The sight openings of casing 8 may be covered by glass in a manner common in illuminated signals and it is clear that said glass 20 may be of any desired color, red for instance, to produce the appearance of a red streak of lightning, if desired.

It is to be understood that the term "successively" in the appended claims is to be 25 construed broadly. Also it is to be understood that the term "lightning flash" is to be broadly construed. The lightning flash effect is primarily produced by the creation, across the railroad crossing, of a materially 30 elongated streak of light, i. e., a streak of light that is materially longer than it is wide, and this effect is enhanced by the jerky illumination of this elongated streak. I wish it to be understood that the invention includes 35 any way of producing, across a railroad crossing, the general effect of a lightning flash. Further, it is to be understood that the invention is not limited to the precise construction set forth, but that it includes 40 within its purview whatever changes fairly come within either the terms or the spirit of the appended claims.

Having described my invention, what I claim is:

45 1. A distinctive signal for railroad crossings, comprising a casing having side walls, the major portions of which are opaque, and sight openings therein extending diagonally of said side walls, said sight openings being 50 of zig zag formation in simulation of a lightning flash, a plurality of partitions in said casing dividing the same into a plurality of compartments longitudinally thereof, electric lamps in said compartments, and means for 55 energizing said lamps successively, the said lightning flash simulation constituting the only illumination in conjunction with said signal.

2. A distinctive signal for railroad crossings, comprising a casing having side walls, a sight opening of zig zag formation formed in one of said side walls simulating the conventional representation of a lightning flash, and extending diagonally of said casing substantially from end to end thereof, electric

lamps within the casing, disposed at spaced intervals there-along, and means for energizing said lamps successively, the lightning flash produced by the successive energization of said lamps constituting the sole illumination employed in connection with said signal.

3. A distinctive signal for railroad crossings, comprising a casing of elongated rectangular formation having side walls, the major portions of which are opaque, and a sight opening therein extending diagonally of said side walls, said sight opening being of zigzag formation in simulation of a lightning flash, a plurality of partitions in said casing, which extend obliquely across said casing, at an angle opposite to that of the sight opening, and dividing the same into a plurality of compartments longitudinally thereof, said sight opening being common to all of said compartments, an electric lamp in each of said compartments, and means for energizing said lamp successively, the said lightning flash simulation constituting the only illumination in conjunction with said signal.

4. A distinctive signal for railroad crossings, comprising a casing of elongated rectangular formation having side walls, the major portions of which are opaque, and a sight opening therein extending diagonally of said side walls, said sight opening being of zigzag formation in simulation of a lightning flash, a plurality of partitions in said casing which extend obliquely across said casing at an angle opposite to that of the sight opening, and dividing the same into a plurality of compartments longitudinally thereof, said sight opening being common to all of said compartments, an electric lamp in each of said compartments, said lamps being supported from the top of the casing at that end thereof where the sight opening lies nearest the top of the casing, and being disposed upon the bottom of the casing at that end of the casing where the sight opening lies nearest the bottom of the casing, and means for energizing said lamps successively, the said lightning flash simulation constituting the only illumination in conjunction with said signal.

5. A distinctive signal for railroad crossings, comprising a casing of elongated rectangular formation, having side walls, the major portions of which are opaque, and a sight opening in each of the side walls of said casing of zig zag formation in simulation of a lightning flash, said sight openings extending diagonally with respect to the side walls of the casing, the sight opening at one side of the casing extending from the upper outer corner of the casing to the lower inner corner thereof, and the sight opening at the other side of the casing extending from the lower outer corner to the upper inner corner,

a plurality of electric lights spaced longitudinally along the interior of said casing, and means for successively energizing the said lights.

5 6. A distinctive signal for railroad crossings, comprising a casing of elongated rectangular formation, having side walls, the major portions of which are opaque, and a sight opening in each of the side walls of said casing of zig zag formation in simulation of a lightning flash, said sight openings extending diagonally with respect to the side walls of the casing, the sight opening at one side of the casing extending from the upper 10 outer corner of the casing to the lower inner corner thereof, and the sight opening at the other side of the casing extending from the lower outer corner to the upper inner corner, a plurality of partitions dividing the interior 15 of the casing into a plurality of independent compartments, individual electric lights for the several compartments, and means for successively energizing said lights.

7. A railroad crossing warning signal having a portion constructed in simulation of a lightning flash, and means for illuminating said portion.

8. A railroad crossing warning signal, having a portion constructed in simulation of a lightning flash, and means for illuminating said portion in a jerky manner.

9. A railroad crossing warning signal, having a portion constructed in simulation of a lightning flash, and means for illuminating said portion in a series of steps.

10. A railroad crossing warning signal, comprising a casing having a sight opening made in simulation of a lightning flash, and means for interiorly illuminating said casing.

40 11. A railroad crossing warning signal, comprising a casing having a sight opening made in simulation of a lightning flash, and means for interiorly illuminating said casing in a step-by-step manner.

45 12. In association with a railroad crossing, a warning signal having a portion constructed in simulation of a lightning flash and disposed substantially transversely across the approach to said crossing, and means for illuminating said portion.

50 13. The combination, in association with a railroad crossing, of a warning signal having a portion constructed in simulation of an elongated lightning flash disposed with its length across the approach to said crossing, and an interior illuminating means for said signal, comprising a plurality of elements disposed along the length of said portion, which are energized successively.

60 14. The herein described method of warning persons about to cross a railroad track of the approach of a train, which comprises flashing across the approach to the track, an illuminated signal of such a nature as to 65 simulate an elongated lightning flash.

15. A railroad crossing warning signal comprising an element having a portion constructed in simulation of a lightning flash, means for illuminating said portion, and means for supporting the signal in such manner with relation to a railroad crossing that the said portion lies obliquely across said crossing.

In testimony whereof he affixes his signature.

JOHN A. MORRISON.
